A. L. EUSTICE.
RENEWABLE CARTRIDGE FUSE.
APPLICATION FILED MAR. 20, 1914.

1,129,459.

Patented Feb. 23, 1915.

UNITED STATES PATENT OFFICE.

ALFRED L. EUSTICE, OF CHICAGO, ILLINOIS, ASSIGNOR TO ECONOMY FUSE & MANUFACTURING COMPANY, OF CHICAGO, ILLINOIS, A CORPORATION OF NEW YORK.

RENEWABLE CARTRIDGE-FUSE.

1,129,459.

Specification of Letters Patent.

Patented Feb. 23, 1915.

Application filed March 20, 1914. Serial No. 825,957.

To all whom it may concern:

Be it known that I, ALFRED L. EUSTICE, a citizen of the United States, residing at Chicago, in the county of Cook and State 5 of Illinois, have invented certain new and useful Improvements in Renewable Cartridge-Fuses, of which the following is a specification.

My invention relates to renewable cartridge fuses, and refers particularly, although not exclusively, to the so-called "ferrule" type of fuses.

It is the object of my invention to provide means for tightly clamping the fusible link 15 between electrically conducting parts in such manner that a tight contact is always maintained between the fuse link and these parts.

It is a further object of my invention to 20 so construct the fuse that the various parts may be quickly and easily assembled and disassembled, so that after the fuse has blown, a new fusible link may be readily placed in position.

These and other objects of my invention 25 will be more readily understood by reference to the accompanying drawings, in which:

Figure 1 is a side elevation of my improved fuse. Fig. 2 is a longitudinal section taken on the line 2—2 of Fig. 1. Fig. 3 is an end elevation of the fuse shown in Figs. 1 and 2. Fig. 4 is a transverse section taken on the line 4—4 of Fig. 2. Fig. 5 is 35 an enlarged fragmentary longitudinal section showing the manner in which the fusible link is clamped in position, and Fig. 6 is a perspective of one of the end washers of the fuse.

The fuse of my invention is of the inclosed 40 type and is provided with a tubular shell 10 of fiber, or other suitable non-conducting material. The fusible link 11 is preferably flat, and extends through the interior of the shell 10. At each end, the link 11 is held in 45 position between the clamping arm 12, fastened to the cap 13, and the clamping arm 14 of the end washer 15. Each end of the link 11 is bent over the washer 15 and is 50 held in position between said washer and the cap 13. The cap 13 is provided with an aperture 16, through which a portion of the end of the link 11 may be seen.

As clearly shown in Fig. 2, each of the end 55 washers 15 abuts against an end of the shell

10 and is held in position by means of the cap 13, which fits over the end of the shell and is held in position by the screw 17, which passes through suitable apertures in the cap 13 and the shell 10. Each of the 60 screws 17 has a threaded end 18, which, as best shown in Fig. 5, engages a threaded aperture in the clamping arm 14 of the end washer 15. The aperture 19 through the clamping arm 12 is slightly larger than the 65 threaded end 18 of the screw 17. The screw 17 is provided with a shoulder 20, which is adapted to engage the clamping arm 12. The link 11 is provided at each end with an aperture 21, registering with the apertures 70 of the clamping arms 12 and 14. It will be evident that when the screw 17 is screwed home, the clamping arm 14 of the end washer 15 will be drawn toward the clamping arm 12 and the fusible link 11 will be 75 tightly clamped in position with an excellent electrical contact.

I have particularly described my invention as adapted for inclosed fuses of the so-called "ferrule" type, but it will be evident 80 that it may also be used for fuses of the knife-blade type by extending the clamping arms 12 to form the blades 22, as indicated in dotted lines in Figs. 1, 2 and 3. It will also be evident that whereas I prefer to use 85 a flat link as the fusible element, a round wire may also be readily employed. In order to allow the gases generated by a violent blowing of the fuse to gradually escape, I preferably employ, near each end of the 90 shell 10, the helical venting passage 23, which causes the gases to become materially cooled before reaching the atmosphere.

When it is desired to disassemble the fuse, as for example after the fusible link has been 95 blown, it is only necessary to remove the screws 17, after which the caps 13 are readily removed from the ends of the shell 10, and the end washers 15 may also be removed. In assembling the fuse, the end washers are first placed in position, the fusible link 11 is then placed in the position indicated in Fig. 2, with the apertures 21 100 registering with the apertures in the clamping arms 12 and 14, the caps are then applied and the screws 17 finally inserted, by means of which the caps are secured in position and the link is securely clamped between the clamping arms 12 and 14.

It will be apparent to those skilled in the 110

art that many changes could be made in the detailed construction of the various parts which I have described without departing from the spirit or scope of my invention.

5 What I claim is:

1. In a cartridge fuse, the combination of a shell, an end cap fitting over each end of said shell, a clamping arm fastened to each of said end caps and projecting within said shell, an end washer between each end of said shell and said cap, said washer being provided with a clamping arm extending parallel with the clamping arm of said cap, a fusible link extending through said shell and between the clamping arms of said caps and said washers, and a screw at each end of said shell, said screw passing through said end cap and said shell and adapted to draw the clamping arms of said cap and said end washer toward each other, thereby securely fastening said link in position, substantially as described.
2. In a cartridge fuse, the combination of a shell, a fusible link passing through said shell, an end cap fitting over each end of said shell, means for electrically connecting said link to said end caps, and a helically disposed venting passage cut in the exterior surface of said shell at each end thereof, whereby the gases formed by the blowing of said fuse will gradually escape through said passage to the atmosphere, substantially as described.
3. In a cartridge fuse, the combination of a shell, an end cap fitting over each end of

said shell, a clamping arm fastened to each of said end caps and projecting within said shell, an end washer between each end of said shell and said cap, each of said end washers having a clamping arm extending parallel with the clamping arm of said cap, and each clamping arm of said washer having a threaded aperture therein, a fusible link extending through said shell and between the clamping arms of said caps and said washers, said link having apertures registering with the apertures in the clamping arms of said washers, and a screw adapted to hold each of said caps in position, said screw engaging the threaded aperture of each of said clamping arms of said end washers and having shoulders engaging each of said clamping arms of said caps, whereby the clamping arms of said caps and said washers may be drawn toward each other and securely hold said link in position, substantially as described.

4. In a cartridge fuse, the combination of a shell, an end cap fitting over each end of said shell, and a helically-disposed venting passage cut in the exterior surface of said shell at each end thereof, whereby the gases formed by the blowing of the fuse will escape through said passages to the atmosphere.

ALFRED L. EUSTICE.
